UNITED STATES PATENT OFFICE.

OBEL JUVET, OF FERNDALE, WASHINGTON.

FILE LEAF FOR ACCOUNT RECORDS.

Original application filed December 21, 1922, Serial No. 608,273. Divided and this application filed October 15, 1923. Serial No. 668,686.

To all whom it may concern:

Be it known that I, OBEL JUVET, a citizen of the United States, residing at Ferndale, in the county of Whatcom and State of Washington, have invented certain new and useful Improvements in a File Leaf for Account Records, of which the following is a specification.

This invention relates to improvements 10 in file leaves for account records.

The primary object of this invention is the provision of a file leaf for account records such as is set forth in my copending application Serial Number 608,273, filed December 21, 1922, including a novel arrangement for the support of account sheets and the like.

A further object of this invention is the provision of a relatively simple and effective type of leaf for filing accounts, particularly well adapted for receiving a plurality of account sheets so that the same may be read with ease.

A further object of this invention is the provision of a novel leaf construction for files.

Other objects and advantages of this invention will be apparent during the course of the following detailed description.

In the accompanying drawings, forming a part of this specification, and wherein similar reference characters designate corresponding parts throughout the several views—

Figure 1 is cross sectional view taken through a file cabinet, showing more particularly the manner in which the improved filing leaves are used therein.

Fig. 2 is a plan view of the novel file leaf.

Fig. 3 is a perspective view of the novel file leaf.

Fig. 4 is a longitudinal cross sectional view taken through the improved file leaf, on the line 4—4 of Fig. 3.

Fig. 5 is a transverse cross sectional view taken substantially on the line 5—5 of Figure 3.

Fig. 6 is a perspective view of a supporting plate detail of this invention.

Fig. 7 is a perspective view of a detail of the improved file.

In the drawings, wherein for the purpose of illustration is shown but the preferred embodiment of the improved file leaf, the

letter A may generally designate a cabinet, such as is specifically set forth in my copending application above referred to, which may receive therein the improved file leaves B.

Referring to the cabinet A, the same may include a casing 10, such as sheet metal, which is placed in an opening 11 of a support 12, which in the instance for which the improved account is provided will be 60 the instrument board of an automotive vehicle. A closure 13 may be hingedly connected, as at 14, to the lower outside edge of the casing 12, having a suitable opening 14^a therein, which may be covered with transparent material, such as celluloid. The closure member 13 is preferably limited in its downward amplitude of movement by sliding brackets 15, which are pivotally connected thereto, and which have a connection 65 70 with the casing 10 so that the lid or closure 13 may only swing to substantially a horizontal position from the normal vertical position in which it is disposed when closed on the casing 10.

The filing leaf B may include a frame 20, and a sheet-supporting plate 21. The frame 20 may be of one piece, or a plurality of pieces as is illustrated in the drawings. It preferably includes side channels 21^a and 22, and a 75 base channel 23. The side channels 21^a and 22 are U-shaped in cross section, with their longitudinal openings facing each other, and with their lower ends riveted, or otherwise secured, as at 26, within the ends of the base 80 channel 23, substantially as is illustrated in Figure 2. The base channel 23 is provided with a longitudinal groove 28 extending along the bottom 29 thereof, which receives therein a shaft or rod 30; said rod being 85 of such length that ends 31 thereof extend outwardly beyond the side surfaces of the frame 20, substantially as is illustrated in Figure 2 of the drawing, so that each leaf B may be suitably pivoted in the casing 10 of 100 the cabinet A.

Each leaf B includes a supporting plate 21, preferably of rigid metal, and which includes a plane body portion 35. At each side margin the plate 21 has the upper and 105 lower attaching flanges 36 and 37 oppositely downturned from each other, into planes substantially at right angles to the body 35 of the plate 21. Thus, the attaching flange 36, which extends for substantially one-half the 110

height of the plate 21 is outturned at right angles from one side surface of the body 35, whereas its adjacent flange 37 therebelow is oppositely outturned from the opposite side surface of the body 35, in the same plane therewith. The upper attaching flanges 36 at opposite side edges of the body 35 are also outturned from opposite side surfaces of the body 35, as is distinguishable from Figure 6 of the drawings. These attaching plates 36 and 37 are provided with longitudinal series of openings 39 therethrough.

Referring to the manner of attachment of the plate 21 within its frame 20, the attaching plates 36 and 37 are disposed in the grooves of the side channels 21^a and 22; said attaching flanges 36 and 37 at each side edge of the body 35 being of a width to be snugly disposed transversely in the groove 20 of the channel in which they are received, to position the body 35 of the plate 21 in a plane which longitudinally intersects the groove of each of the channels 21^a and 22 to sub-divide the same into two pockets, so to speak. As 25 the attaching plates 36 and 37 contact the bight portions 41 of the channels 21^a and 22 they are secured thereto, as by rivets 42, which are secured through apertures 39 of the attaching wings or flanges 36 and 37.

From the foregoing description of the leaf B it is apparent that a U-shaped pocket or groove is provided by the channels 21^a, 22 and 23 at each side surface of the plates 21, and which pockets are open at the outer and 35 top edges of the frame channels 21^a and 22, so that a record sheet may be readily slipped therein on both sides of the body 35 of plate 21. To maintain record sheets in such position it is preferred to provide resilient clips 40 in the pockets of each channel member, adjacent the outer ends of the channel members 21 and 22, which have their resilient portions arcuated and urged into engagement with the body 35, substantially as is 45 illustrated in Figure 4 of the drawings. Thus, a sheet or other article slipped into the pocket will be forced by the clips 45 into engagement with the body 35 of the plate 21, to be held in position against liability of 50 accidental detachment.

On the bight portion 41 of the channels 21^a and 22, it is preferred to provide outwardly struck catches or projections 47, which may cooperate with resilient clips 50 to maintain the leaves in stable supported 55 relation when closed in the casing 10, and as is more specifically described in my copending application above referred to.

It is apparent from the foregoing that 60 record sheets may be slipped into the file B on both sides of the body portion 35 of the plate 21 thereof. The sheet which is slipped over the forward surface of the body of plate 21 may be read when the leaf B is in its vertical position, substantially as is illustrated 65

by the dotted lines in Figure 1 of the drawings. The sheet to the rear of the plate 21 may be read when the leaf B is in its down position, substantially horizontally located, as is shown in the position of the leaves illustrated in Figure 1.

While I have illustrated the frame 20 as of the construction set forth in my copending application above referred to, it is contemplated to manufacture the frame 20 of channels which may be of the same size, any suitable provision being made in the base channel to receive the shaft 30. Various other changes in the shape, size, and arrangement of parts may be made to the form of invention herein shown and described, without departing from the spirit of the invention or the scope of the claims.

I claim:

1. As an article of manufacture, a filing leaf for file cabinets comprising a plate having opposite sides provided with attaching flanges, and a U-shaped frame formed of channel members and having said plate positioned therein with its attaching flanges connected to the side arms of the frame, portions of the frame at opposite sides of the plate providing pockets for receiving sheets of records therein, and means in said pockets for frictionally gripping the sheets of records placed therein.

2. As an article of manufacture, a filing leaf for file cabinets comprising a body plate having its side edge portions provided with upper and lower flanges, the upper flanges 100 extending in an opposite direction to the lower flanges and the flanges at one side extending in an opposite direction to corresponding flanges at the opposite side of the body plate, channels having the side portions of the body plate extending therein with the flanges secured to the channels, said channels providing pockets on each side of the plane of said body plate, and spring means in said pockets for retaining record sheets therein.

3. As an article of manufacture, a filing leaf for file cabinets comprising a plate, channels, means connecting the opposite side edges of said plate in the pockets of said channels whereby the plane of said plate intersects the pockets of said channels longitudinally to provide spaces in said channels at each side of the plane of said body plate, and spring clips carried by the flanges of 110 the channels in the spaces on each side of said body plate.

4. As an article of manufacture, a filing leaf for file cabinets comprising a supporting plate of plane formation having the side edges thereof outturned in opposite directions at right angles to the plane defined by said plate, channels defining grooves therein in which receive the oppositely turned flanges of said plate to provide spaces in 120 130

said channels at each side of the plane of said plate, a channel at the lower edge of said body plate, and a pintle carried in said lower channel having the ends thereof extending laterally of the file leaf.

5. As an article of manufacture, a file leaf comprising substantially U-shaped frame of channel formation, a plate secured in said frame and spring means within the 10 grooves of said channel-shaped frame and engaging opposite faces of said plate for securing sheets in position therein.

6. As an article of manufacture, a file leaf

of the class described, comprising substantially U-shaped side members providing 15 grooves extending longitudinally thereof, a supporting plate secured to said side members in intersecting relation with the grooves of the same to permit sheets to be slipped in the grooves of said side members for 20 resting against said plate and spring clips in said grooves and engaging opposite faces of said plate to frictionally hold record sheets in engagement with said plate.

OBEL JUVET.
